UNITED STATES PATENT OFFICE.

ROBERT L. WELCH, OF WILLIAMS, CALIFORNIA.

SUBMARINE-GROWTH CUTTER.

1,269,139.

Specification of Letters Patent. Patented June 11, 1918.

Application filed November 2, 1916. Serial No. 130,300.

To all whom it may concern:

Be it known that I, ROBERT L. WELCH, a citizen of the United States, residing at Williams, in the county of Colusa and State of California, have invented a new and useful Improvement in Submarine-Growth Cutters, of which the following is a specification.

My invention relates to submarine growth cutter wherein horizontal and inclined cutting mechanisms operate to clear a submerged path for boats and the like; and the objects of my invention are—

10 First, to provide an improved submarine growth cutter;

15 Second, to provide improved means of the character described that may be readily and easily submerged or emerged;

20 Third, to provide an improved device of the character described having means whereby the same may be raised or lowered in an operative position to various elevations; and

25 Fourth, to provide an improved device of the character described that shall be simple and cheap in construction and operation and also possessing a maximum efficiency.

I accomplish these several objects by means of the preferred form of the device disclosed in the drawings forming a part of the present specification wherein like characters of reference are used to designate similar parts throughout the said specification and drawings, and in which—

30 Figure 1 is a side elevation of the bow of a boat disclosing my invention applied thereto.

Fig. 2 is a plan view of Fig. 1.

Fig. 3 is a broken vertical section, on an enlarged scale, of the lower portion of the device disclosing the manner in which both 40 cutting mechanisms are operated from the same power shaft.

Fig. 4 is a bottom plan view of Fig. 2 disclosing the manner in which the horizontal cutter bar is operated.

45 Fig. 5 is an enlarged transverse sectional view taken on line X-X of Fig. 1 in the direction indicated by the arrows.

This device is intended to cut submerged paths through marshes where tules, submarine growths and the like flourish to such an extent that boats and other water crafts are prevented from passing therethrough, or where such passage is impeded by reason of such growth.

50 The hereinafter described invention while intended to be submerged when in an opera-

tive position is also capable of being not only raised to any desired elevation when submerged but also of being emerged from the water or inclined at various angles. 60

Referring now to the drawings the numeral 1 is used to designate the bow of a boat or the like to which is secured plate 2 having an inclined sleeve 3 pivotally mounted thereon. 65

A tubular member 4 is slidably and rotatably mounted within the sleeve 3 and is normally held against movement relatively to the sleeve 3 by means of a split ring 6 secured to said sleeve 3 and arranged to be 70 expanded or contracted to engage or disengage the tubular member 4 by means of a securing latch 7.

The upper end of the tubular member 4 is provided with suitable handles 8 by means 75 of which said members 4 may be raised or lowered or partially rotated within the sleeve 3.

The tubular member 4 is also provided with a slot 9 having an inclined cutting 80 mechanism in the shape of serrated teeth 11 arranged adjacent said slot 9. A serrated cutting bar 12 is slidably mounted within the slot 9 to operate in conjunction with the serrated teeth 11 and is provided with a pair 85 of sleeves 14 having annular inclined cam slots 16 therein engaged by pins 17 on a shaft 18 rotatably mounted within the tubular member 4.

The lower end of the shaft 18 is operatively connected to a vertically disposed 90 shaft 19, having a disk 21 and pin 22 thereon, by means of a suitable universal joint 23.

The disk 21 and shaft 19 are arranged to operate the horizontally disposed cutting 95 mechanism which comprises a bar 24 having teeth 25 upon which is slidably mounted a cutting bar 26 having teeth 27 arranged to operate in conjunction with the teeth 25 of the bar 24. 100

The cutting bar 26 is provided with a central or operating slot 28 arranged to be engaged by the rotating pin 22 of the rotating disk 21 whereby said cutting bar 26 may be continually reciprocated. 105

Longitudinally disposed slots 29 within the cutting bar 26 are arranged to receive suitable pins 32 secured to the bar 24 whereby said cutting bar 26 may be slidably held in position. 110

The shaft 18 is operatively connected at its upper end to a flexible drive shaft 33

whereby said shaft and both cutting mechanisms may be operated.

The operation is as follows:

Assuming the parts to be in an operative position as disclosed in Fig. 1 of the drawings it is obvious that as the shaft 18 within the tubular member 4 is rotated a reciprocating movement will be imparted to both cutting bars 12 and 26 which operating in conjunction with their respective stationary teeth 11 and 25 will operate to cut a submerged path through tules or other submarine growth and thereby provide a clear path for the passage of water craft.

15 The upper or inclined cutting mechanism is provided for the purpose of preventing the debris or growth that has been cut away from accumulating on the tubular member 4.

20 The depth of the path to be cut may be easily adjusted or predetermined by loosening the securing latch 7 of the split ring 6 and raising or lowering the tubular member 4 by means of the handles 8 on the upper end thereof and again securing the 25 ring 6.

25 The entire device may be emerged and moved to an inoperative position by elevating the said device on its pivot as disclosed in dotted lines in Fig. 1 of the drawings.

30 As the tubular member 4 is rotatably as well as slidably mounted within the sleeve 3 it is evident that the angle of the lower or submerged cutting mechanism may be altered by loosening the ring 6 and partially 35 rotating the tubular member 4 within the sleeve 3 until the desired angle is attained.

40 It is obvious from the foregoing that I have provided an improved submarine growth cutter adapted to be easily submerged or emerged and to cut a submerged path through tules or other submarine growth thereby rendering navigable marshes and the like.

45 It is also obvious that I have provided an improved submarine growth cutter that is simple and cheap in construction and operation and yet possessing a maximum amount of efficiency.

Having thus described my invention what 50 I claim as new and desire to secure by Letters Patent is—

1. A submarine growth cutter comprising

horizontally and vertically disposed cutting mechanisms pivotally and slidably mounted upon the bow of a boat or the like; and 55 means for operating both cutting mechanisms simultaneously.

2. A submarine growth cutter comprising a horizontally disposed cutting mechanism; means for operating the cutting mechanism; 60 and means for pivotally and slidably mounting the cutting means on the bow of a boat or the like whereby said cutting means may be submerged below water at various elevations. 65

3. A submarine growth cutter comprising an inclined sleeve pivotally mounted upon the bow of a boat or the like; a tubular member slidably and rotatably mounted within the sleeve; means for locking the 70 tubular member within the sleeve; a horizontally disposed cutting mechanism secured to the lower end of the tubular member; and means extending through the sleeve 75 for operating the cutting mechanism. 75

4. A submarine growth cutter comprising an inclined sleeve arranged to be secured to the bow of a boat or the like; a horizontally disposed cutting mechanism; a tubular member slidably mounted within the inclined sleeve and arranged to support the cutting mechanism whereby said cutting mechanism may be submerged and emerged; 80 and means for operating the cutting mechanism. 85

5. A submarine growth cutter comprising an inclined sleeve pivotally mounted upon the bow of a boat or the like; a tubular member slidably and rotatably mounted within the sleeve; means adapted to secure 90 the tubular member against movement within said sleeve; an inclined cutting mechanism secured on the tubular member and extending to the lower portion thereof; a horizontally disposed cutting mechanism 95 secured to the lower end of the tubular member; and means extending through the tubular member and operatively connected to both cutting mechanisms whereby same may be operated. 100

In witness whereof I hereunto set my signature.

ROBERT L. WELCH.
